ROTARY BLADED STRUCTURE

Rallston M. Sherman, Glastonbury, and John Carlberg and George R. Neumann, West Hartford, Conn., assignors to The Silent Glow Oil Burner Corporation, Hartford, Conn., a corporation of Connecticut

Original application December 27, 1935, Serial No. 56,334. Divided and this application June 11, 1936, Serial No. 84,694

8 Claims. (Cl. 230—114)

This invention relates to rotary bladed structures, and is a division of our application, Serial No. 56,334, filed December 27, 1935.

One object of the present invention, among others, is to provide a rotary impeller of simple construction and particularly for the purpose of delivering air or other gaseous fluid, said impeller having blades which are movable each on an axis extending outwardly from the axis of rotation and movement of which may be usefully availed of to cut off, as may be required, further substantial passage of fluid on the stoppage of the impeller or to adjust the working pitch of the blades to vary the capacity of the impeller.

Another object of the invention is to provide a rotary structure having movable blades of such size, shape and relation as to form a substantial closure for an air delivery or other aperture, the blades, whether or not having any air impelling function, being movable in response to the rotation of the structure to open said aperture and to close the latter on the stoppage of rotation.

These and other objects of the invention will be best understood by reference to the following description when taken in connection with the accompanying illustration of one specific embodiment thereof, while its scope will be more particularly pointed out in the appended claims.

In the drawings:

Fig. 1 is a side elevation, partly broken away, showing an air impeller fan with the blades closed, and also showing the relation of the fan to the surrounding walls of an air conduit and to a driving motor;

Fig. 2 is a similar side elevation showing the blades open;

Fig. 3 is a front elevation in partial section showing the air fan with the blades in closed position, looking from the open or air entering end;

Fig. 4 is a section in elevation, taken on the line 4—4, showing the motor with its supporting means;

Fig. 5 is a detail in cross-section, on the line 5—5, showing one of the motor supporting lugs; and

Fig. 6 is an elevation showing the impeller, looking from the delivery side, also with the blades in closed position.

In the embodiment of the invention selected for illustration, there is shown in the drawings a rotary air impeller 7 of the propeller or pitched blade type, designed in this particular case to deliver air to the combustion chamber of a fur-

nace in connection with an oil burner, the cylindrical body or casing 9 representing the tubular air conduit for an oil burner, through which air passes from the entering end 11 to the delivery mouth of the conduit. At the air receiving end of the casing there is provided a sleeve 13 telescopically fitting the rear end of the tubular member 9, this sleeve serving the function of surrounding the impeller 7 and also of supporting the motor 15 employed for driving the impeller. The motor casing is supported by the sleeve 13 through a plurality of equally spaced arms 19 (herein four in number), formed integrally with the sleeve and extending part way radially inward, each arm carrying a laterally extending lug 21 bolted to a boss on the motor casing. The shape and arrangement of such supporting lugs are best indicated in Figs. 4 and 5. This arrangement suspends the motor on the supporting sleeve in overhanging relation within the casing 9, leaving an annular space between the cylindrical casing and the motor to serve as a part of the air conduit. The faces 23 of the arms 19, which confront the closely adjacent rotating blades of the air impeller, serve as air cut-off means, as hereinafter more fully explained. The inner walls of the sleeve 13 are tapered inwardly and forwardly, providing a bore having a contracted air delivery mouth or aperture closely surrounding the blades of the fan or impeller, as shown in Fig. 1.

The described arrangement is merely illustrative as one application of the invention, the specific mounting of the motor and its relation to the fan being immaterial, the specific type of air conduit being unimportant, and the same being employed to illustrate one form of air delivery aperture, such as the mouth of the sleeve 13, through which the air impeller is designed to control the delivery of air.

Referring more particularly to the construction of the air impeller, as best shown in Figs. 1, 2, 3, and 6, the same is provided with a sleeve-like hub 25 secured to the rearwardly projecting end of the motor shaft 21. The fan or impeller comprises a series of thin, light, metallic blades 29 (herein six in number), approximately flat but slightly concaved toward the air delivery side of the fan, each blade being of a generally triangular shape with an outer arc-shaped edge. Each blade at the inner and outer ends of one edge has a small corner flange 31 bent at right angles, by means of which the blade is pivotally mounted on a pin or small rod 33 and on which it is held by a small disk-shaped cap piece 35 fixedly se-

cured on the end of the pin. Each rod is fixedly secured to the fan hub 25 and projects outwardly therefrom but is also pitched or inclined somewhat forwardly in the direction of air delivery and with relation to the axis of rotation of the impeller.

A torsion spring 37 encircles each pin, having one end fixed to the pin and the other end extending over and lying against the face of the 10 adjacent fan blade so that normally, when the fan is at rest, the blades are urged by the light pressure of the spring in a direction to cause them to assume a closed position, or that shown in Figs. 1, 3, and 6, in which position they are 15 each maintained by the small stop finger 39 projecting from the lower end of the free side of the blade. In the described relationship this finger encounters and is stopped by the pivoting pin 33 of the next adjoining blade.

20 The pivoted edge of each blade extends somewhat beyond the pivoting rod, and when the blades are in closed position this extension is there overlapped by the free edge of the next adjoining blade. Accordingly, when the fan is 25 at rest and the blades closed, the latter form a substantially continuous closure in the general form of a truncated cone, substantially closing the air delivery aperture of the sleeve 13, as best seen in Fig. 1, there being left between the edges 30 of the blades and the walls of such aperture only a reasonable mechanical clearance to permit the rotation of the fan and the subsequent opening movement of the blades.

When the fan is started into rotation, however, the forward inclination of the pivotal axes of the blades causes the latter to move under centrifugal force about the pivot pins and to open up against the opposing pressure of the spring 37 into some such position as is represented in Fig. 2. This opening movement continues as the speed of rotation increases, until either positively arrested or until the center of gravity of each blade reaches its maximum radial distance from the axis of rotation. As soon 45 as the opening movement of the blades has been initiated under centrifugal force, it is further aided by the reaction of the air across which the blades are then cutting. The walls of the air conduit within the sleeve are enlarged by being 50 rearwardly flared to permit the required opening movement of the blades while closely surrounding the latter in all positions assumed.

The angular inclination of the blade axes to the axis of rotation may be varied within wide limits, 55 dependent on the weight of the blades, the position of the center of gravity of each and the strength of the closing spring to be overcome. With a relatively heavy blade or with one weighted near its peripheral margin or with a 60 relatively lighter spring, a lesser angle of inclination may be employed, or with a lighter blade or a heavier spring, a greater inclination may be required. With light sheet metal blades of the form shown and a relatively light spring, 65 we have found that an angle of inclination of the order of approximately 25° (as shown in the drawings) insures a positive, certain opening of the blades when the impeller is rotated at speeds of the order of 500 R. P. M. or more.

70 The working pitch of the blades and the resulting capacity of the fan for air delivery are dependent on the extent of this opening movement. This may be predetermined and the air supply definitely fixed by the simple use of an adjustable blade stop. This is herein provided by

means of the sleeve 41 (Figs. 1 and 2) which is adjustably threaded on the outside of the fan hub 25 and has its forward edge presented to the stop finger 39 of each blade, as shown in Fig. 2. The stop 41 may be adjusted to any desired position lengthwise the threaded portion of the fan hub and there held fixed by the set screw 43, thereby providing means whereby the opening movement of the blades may be adjusted to any point between zero opening and maximum. The air supply may therefore be preadjusted by the adjustment of the fan alone and without the use of any valve or shutter extraneous to the fan.

10 The use of the self-closing air impeller blades provides the important function of automatically stopping further passage of air through the air delivery aperture as soon as the fan ceases to function in creating its forced draft. When the fan is at rest, it effects a substantial closure of the air conduit and automatically seals off the 15 aperture against the passage of air.

To accelerate the progressive movement of the air from the air entering end 11 through the air delivery aperture and the conduit, which air movement would otherwise in part tend to rotate 20 without progression, the air cut-offs 23 on the arms 19 are employed which lie immediately in front of the fan and project radially across the 25 annular path of the rotating body of air as it leaves the fan, the impeller rotating in a clockwise direction as viewed from the front in Fig. 4. If the number or effectiveness of such cut-off members is increased, the rotary movement of the air is diminished and its progressive movement 30 further increased.

35 Claims relating to the cooperative relationship between the features of the rotary bladed structure and those of the liquid fuel burner are separately claimed in application, Serial No. 56,334, of which this is a division. Certain features of 40 improvement not herein disclosed are claimed in the subsequently filed co-pending application of Sherman and Carlberg, Serial No. 138,604, filed April 23, 1937.

45 While we have herein shown and described for the purposes of illustration one specific embodiment of the invention and one specific application thereof, it is to be understood that the latter has application to a wide variety of uses and, furthermore, that extensive changes may be made 50 in the form, relative arrangement and details of the parts herein shown, all without departing from the spirit of the invention.

We claim:

1. The combination with an air delivery conduit having an air delivery aperture, of a rotary air impeller in said conduit in operative relation to said aperture, said impeller having blades rotatable each about an outwardly extending axis inclined with relation to the axis of impeller rotation, and mounted to turn to an air-impelling position in response to rotation of the impeller, said blades being of such size, shape and relation as to form a substantial closure for said aperture, and means for automatically moving said blades to a closed position when said impeller is at rest, whereby, when said impeller is at rest, said aperture is substantially closed and when rotated said blades are swung about their axes and opened to an air impelling position.

2. A rotatable air impeller having a plurality of blades rotatable each about an outwardly directed axis and mounted to turn to an air-impelling position in response to centrifugal force on rotation of the impeller, the blades being of 75

such size, shape and relation as to form a substantial closure for an air delivery aperture in relation to which the impeller may be operatively positioned, the axis of each blade being inclined with relation to the axis of rotation of the impeller, and means for automatically moving said blades to a closed position when said impeller is at rest whereby, on rotation of the impeller, the blades are opened by centrifugal force 10 to an air impelling position and on stoppage thereof are moved to a closed position.

3. A rotatable air impeller having a plurality of blades rotatable each about an outwardly directed axis, and mounted to turn to an air-impelling position in response to rotation of the impeller, the blades being of such size, shape and relation as to form a substantial closure for an air delivery aperture in relation to which the structure is operatively positioned, the axis of each blade being inclined with relation to the axis of rotation of said structure, and means for automatically moving said blades to an aperture-closing position when said impeller is at rest, whereby on rotation of the structure the 20 blades are opened by centrifugal force to an aperture-opening position and on stoppage thereof are moved to an aperture-closing position.

4. The combination with a structure presenting an air supply aperture, of a rotatable structure in operative relation thereto carrying a series of blade sections pivoted each near one edge on an axis extending outwardly from and inclined to the axis of rotation of said carrying structure, the free edge of one blade section overlapping the pivoted edge of the next adjacent blade section, said blade sections being of such size, shape and relation as to form a substantial closure for said aperture when said carrying structure is at rest, means for urging said blade sections into over-lapping and aperture closing relation on the stoppage of rotation of said carrying structure, said blades being adapted on rotation of said carrying structure to move under centrifugal force to an aperture opening position, and means to rotate said structure.

5. The combination with a structure presenting an air supply aperture, of a rotatable structure operatively related to said aperture and carrying a plurality of blades mounted to turn each about an outwardly extending axis inclined with relation to the axis of rotation of said carrying structure, said blades being of such size, shape and relation as to form a substantial closure for said aperture when moved to one posi-

tion, means to rotate said structure, and means acting automatically on the stoppage of rotation of said structure to move said blades to maintain an aperture closing position, said blades being automatically movable in response 5 to the rotation of the carrying structure to move to an aperture opening position.

6. The combination with a structure presenting an air supply aperture, of a rotatable air impeller in operative relation to said aperture and having a plurality of impelling blades mounted each to turn about an axis extending outwardly from the axis of rotation of the impeller, means aided by centrifugal force for causing the automatic movement of the blades about their axes 15 on rotation of the impeller to an aperture opening and air impelling position, said blades being of such size, shape and relation to the aperture as to form a substantial closure therefor when moved to another position, means acting automatically 20 on the stoppage of the impeller rotation to move said blades to maintain an aperture closing position, and means for rotating said impeller.

7. The combination with a structure presenting an air supply aperture, of a rotatable structure in operative relation thereto and having a plurality of blades movably mounted on said rotatable structure, means aided by centrifugal force for causing the automatic movement of the 30 blades to an aperture opening position on rotation of the rotatable structure, said blades being of such size, shape and relation to the aperture as to form a substantial closure therefor when moved to another position, means acting automatically 35 on the stoppage of rotation of such rotatable structure to move the blades to maintain an aperture closing position, and means for rotating said rotatable structure.

8. The combination with a structure having an aperture, of a rotatable impeller in operative relation thereto and having a series of concavo-convex blades mounted each on an axis at the convex side of the blade near one edge thereof, said axis extending outwardly from but inclined 45 to the axis of rotation, said blades being normally moved to an overlapping position to form a conical structure substantially closing said aperture, and said blades being each movable about its axis under centrifugal force to open said aperture when the impeller is rotated.

RALLSTON M. SHERMAN.

JOHN CARLBERG.

GEORGE R. NEUMANN.
